UNITED STATES PATENT OFFICE

EDMUND W. WOODRUFF, OF WASHINGTON, DISTRICT OF COLUMBIA.

IMPROVED OIL-CAN AND POWDER-CANISTER.

Specification forming part of Letters Patent No. 43,652, dated July 26, 1864.

To all whom it may concern:

Be it known that I, EDMUND W. WOODRUFF, of the city and county of Washington, in the District of Columbia, have invented a new and useful Improvement in a Combined Polish-Canister and Oil-Can for Army, Navy, and other Purposes; and the following is a full, clear, and exact description of the same, reference being had to the accompanying drawings, making a part of this specification, in which—

Figure 1 shows an exterior view of canister and oil-can put together complete. Fig. 2 shows the interior arrangement, with partitions, chamois, and oil-tube. Fig. 3 is the oil-can with the oiler attached. Fig. 4 is the perforated top to polish-canister. Fig. 5 is the screw-cap to oil-can. Fig. 6 shows the oiler detached.

My invention consists in the construction and arrangement of a canister for containing polishing material, in combination with an oil-can and oiler.

To enable others skilled in the art to make and use my invention, I will describe it more fully, referring to the drawings and to the letters of reference marked thereon.

I make the polish-canister A of metal—such as tin, zinc, roll brass, or copper—in an oval or any other convenient form, and of such sizes as to suit the convenience of persons requiring their use, in the top of which is fitted a perforated lid or cover, a, in such manner that it can be removed to fill the canister A with emery, tripoli, rotten-stone, or any other polishing-powder. The perforated lid a serves to prevent the polishing-powder from being emitted except in small quantities.

The oil-can B, which forms the cap or cover

to the canister A, is constructed in a similar form to the canister, it having a partition, b, in about the middle, which is the bottom of the oil-can, leaving a space, C, below and between the perforated lid a, in which to pack the oiler D and rubber when not in use. The orifice e in the top is secured by a screw-cap, d, having a gasket, i, underneath, to prevent leakage, the cap d being secured to the can B by a chain or cord, f. When in use, the cap d is removed and the tapering tube or oiler D is attached, as seen in Fig. 3.

The advantages of my invention are at once acknowledged and appreciated by all who have had experience in camp. The army regulations require that all arms and equipments shall be kept clean and bright, and in order to accomplish this every soldier should be furnished with something of this nature. The portability and compactness of this arrangement, together with the economy in which the material can be applied, there being no danger of spilling the polishing-powder or oil, or of using any superfluous quantity, make it the most convenient article that can be had for this purpose.

Having fully described my improved combined polish-canister and oil-can, what I claim as new and useful, and desire to secure by Letters Patent, is—

The arrangement of a canister for containing cleaning or polishing material, in combination with an oil-can and oiler, in the manner herein specified, and for the purposes set forth.

E. W. WOODRUFF.
